(57) **CLAIM**

The ornamental design for a door for a gun cabinet, pistol box, ammunition box, security safe, or the like, as shown and described.

DESCRIPTION

FIG. 1 is a perspective view of a first embodiment of the design.

FIG. 2 is a top view of a first embodiment of the design.

FIG. 3 is an elevation view of a first embodiment of the design.

FIG. 4 is a side view of a first embodiment of the design.

FIG. 5 is a perspective view of a second embodiment of the design.

FIG. 6 is a top view of a second embodiment of the design.

FIG. 7 is an elevation view of a second embodiment of the design; and,

FIG. 8 is a side view of a second embodiment of the design. The broken line showings of a cabinet and a logo are for illustrative purposes only and form no part of the claimed design.
